Specification for Design.

Patented May 11, 1920.

Application filed May 10, 1919. Serial No. 296,246. Term of patent 14 years.

To all whom it may concern:

Be it known that I, JAMES P. HADDIX, a citizen of the United States of America, residing at Crawford, in the county of Dawes and State of Nebraska, have invented a new, original, and ornamental Design for a Combined Pocket-Knife and Bottle-Opener, of which the following is a specification, reference being had to the accompanying drawing, forming part thereof.

In the drawing:

Figure 1 is a side elevation of a combined pocket knife and bottle opener, showing my design,

Fig. 2 is a rear view of the same.

I claim:

The ornamental design for a combined pocket knife and bottle opener, as shown.

JAMES P. HADDIX. [L.S.]
